HAND LANTERN

Alfred C. Korte, St. Louis, Mo., assignor to Metal-craft Corporation, St. Louis, Mo., a corporation of Missouri

Application February 26, 1934, Serial No. 712,979

13 Claims. (Cl. 240—10.63)

This invention relates to improvements in battery operated electric lanterns and more particularly to lanterns which may either be carried in the hand or set upon a table. In previous devices of this character a number of dry cells of the flash light battery type have been loaded into a container which was provided with an electric light bulb and a switch in such a manner that the current from the batteries was carried to the switch thru the cover and base of the casing. This set up resulted in electrolytic action between the cover and base of the casing, particularly at the joint where the two are telescoped together. This electrolytic action resulted in corrosion and frequently in a bad circuit connection at this point. If the casing was painted it was necessary to scrape away the paint at the point where the cover slides into the base. The necessity of scraping away the paint gave rise to various obvious difficulties, one of which was the concentration of the corrosion at one point.

An object of this invention is to provide an electric hand lantern of a new and improved type in which the cover and the base of the battery casing do not both form a part of the circuit.

A further object of the invention is to provide an electric hand lantern having a battery casing having two parts adapted to be telescoped together and which do not have to be in electrical contact.

A further object of this invention is to provide a generally new and improved hand lantern.

Other objects will appear from the following description and accompanying drawings, referring to which:

Figure 1 shows a side elevation of the lantern according to my invention.

Figure 2 shows a sectional elevation of the lantern according to my invention.

Figure 3 shows a sectional elevation of the top portion only of the lantern, the section being taken along the lines 3—3 of Figure 2 looking in the direction of the arrows.

Figure 4 is a fragmentary sectional elevation of the lantern taken along the lines 4—4 of Figure 5.

Figure 5 is a sectional plan view of the lantern with the batteries removed, the section being taken along lines 5—5 of Figure 2 looking in the direction of the arrows.

Figure 6 is an inverted sectional plan view taken along the lines 6—6 of Figure 2 looking in the direction of the arrows.

Figure 7 is a plan view of the central contact member.

Figure 8 is a side elevation of the central contact member.

The reference numeral 1 indicates the battery casing which is telescopically mounted on a base 2 which is provided with a stand 3 so that the device may be set on a table to be used as a table lamp if desired. The above described parts are preferably formed of sheet metal and may be painted if desired as there is no necessity for securing an electrical contact between these parts. The base is provided with a lower insulating gasket 4 which is perforated in the center as indicated at 5 to receive the central part of an electric light bulb 6. The threaded base of the bulb is screwed into a ferrule 7 which is riveted into the base of the lamp as indicated in Figure 2. A reflector 8 is held in position by the ferrule 7.

The upper insulating washer 9 together with the lower insulating washer is held in assembled relation with the base by means of the rivets 10. A central contact member 11, formed as indicated in Figures 7 and 8, is mounted between the upper and lower insulating washers and has a pair of lugs 12 which extend upwardly thru a pair of corresponding slits 13 in the upper insulating washer and are bent outwardly to a horizontal position above the upper insulating washer as indicated in Figure 5. The central terminal of the electric light bulb contacts with the member 11 and the lugs serve as contacts for the bases 14 of the batteries 14. The batteries are held in position by means of the separating partition 15 which is formed of two V-shaped strips of sheet metal. The center of the V is flattened out so that the two pieces will make contact with each other when they are pressed into place. The ends of the V's are provided with outwardly turned flanges 16, which resiliently contact with the outer casing 1 so that the separating partition will be rigidly held in place by friction without the necessity for spot-welding or riveting, although this may also be done if desired.

Both the upper and lower insulating washers are perforated in two places as indicated at 17 and a pair of bosses 18 are formed on the upper side of the base to extend thru and project slightly beyond the openings 17 so as to form contacts for the central terminal of a pair of batteries as indicated in Figure 4. It may be noted that the central terminals of the batteries may, if desired, rest on the lugs 12 and the bases of the other pair of batteries may rest on the bosses 18 as long as the batteries are so arranged as to be in series.

The upper part of the battery casing 1 is pro-

vided with an insulating disc 19 which is held in position on the closed end of the casing by means of suitable rivets 20. A pair of contact members 21 are riveted to the insulating disc by means of rivets 22. Each of the contact members 21 is provided with a pair of spring contact members extending downwardly at an angle into the battery casing to contact the central terminals or bases of the batteries according to the way in which they may be inserted. Each contact member 21 is provided with an extension 23 which extends upwardly thru a slit 24 in the disc 19, and is then turned to a horizontal position.

The switch comprises a device for establishing an electrical connection between the extensions 23. To this end a flexible contact member 25 is riveted to the insulating disc 19 by means of one of the same rivets 22 which hold one of the contact members 21. The free end of the contact member 25 may bend downwardly and touch both of the extensions 23 of the contact member 21 so as to establish an electrical connection therebetween. An insulating member 26 is mounted on top of the flexible member 25 and is preferably held in position by the rivets 22. The rear end of the contact member 25 is bent downwardly as indicated at 27 and extends thru a corresponding slit in the insulating disc 19 to assure its remaining in operating position and not rotating about the rivets 22.

The member 28 forms the operating handle for the switch which is slidably mounted on the closed end of the container 1. The member 28 is provided with a pair of lugs 29 which extend downwardly thru a corresponding slit in the cover and are bent over to secure the member 28 to the lower switch member 30 which is provided with a downwardly turned cam member 31. A suitable indentation or inwardly extending boss 32 serves as a detent for the left hand end of the member 30 as indicated in Figure 3 which is provided with a suitably curved end to slide over the stop and be held in position thereby so that the switch will remain in either "on" or "off" position. A washer 33 preferably made of graphite paper or other anti-friction material is provided to assist in keeping rain water from entering the opening thru which the lugs 29 extend. In case any water should enter the casing, suitable openings 34 are provided in the base to drain it out.

The casing 1 is provided with a base 35 which is pivotally attached thereto by means of rivets 36 attached to the bosses 37 which are formed on each side of the casing. The casing 1 telescopes into the base 2 as previously described and is held in assembled relation by means of bayonet slots 38. Any number of bayonet slots are used, but if more than two slots are used they should be unequally spaced around the periphery of the casing so that the individual battery compartments 39 as defined by the partition 15 will not come in the wrong relation to the contact members 12 and the bosses 18.

In operation either two or four batteries may be loaded into the compartment 39, provided, however, that one battery at least should be in one of the upper compartments with respect to Figure 5 so that one of its terminals will contact with one of the members 12 and another battery should be in one of the lower compartments with reference to Figure 5 so that one of its contact members will be in contact with one of the bosses 18. Also if the central terminal of a battery contacts with the member 12 then the base of the other battery must contact with the boss 18 and vice versa, so as to establish a

series connection thru the member 11, the central terminal of the light bulb, the filament, the base of the bulb, the ferrule 7, the base of the container and the boss 18. Having fitted the batteries into the compartments 39, the resilient members 21 contact with the upper end or terminals of the batteries and when the switch operating member 28 is moved to the left with respect to Figure 3, the contact member is pressed downwardly to form a connection between the members 23 and the circuit is completed.

I claim:

1. In a device of the class described, a base member, a flange, an upper insulating washer, a lower insulating washer, a contact member mounted between said insulating washer, said base member and lower insulating washer being provided with openings thru which the base of an electric light bulb may extend, said contact member extending upwardly thru said upper insulating washer to contact with the base of a battery, and rivets passing thru said upper and lower insulating members, said base and said stand to hold said parts in assembled relation.

2. In a device of the class described, a sheet metal base member, upper and lower insulating washers mounted on said base member, registering openings in said base member and the lower insulating washer, a contact member having a portion mounted between said insulating washers and exposed to said opening, said contact member having another portion extending upwardly thru said upper insulating washer and being bent over to form a battery contact, registering openings in said insulating washers and a boss formed in said base member and extending upwardly thru said registering openings to form a battery contact.

3. In a device of the class described, a sheet metal base member having a central opening and a pair of upwardly extending bosses, a lower insulating washer having an opening registering with the opening in said base member and other openings registering with said bosses, an upper insulating washer mounted on said lower insulating washer, a contact member having a portion extending thru and above said upper insulating washer, and another portion between said upper and lower insulating washers, said bosses and said contact member being adapted to engage battery terminals.

4. In a device of the class described, a casing divided into four compartments each of said compartments being adapted to receive a battery, a base for said casing, means for connecting said base with the batteries in two of said compartments, a contact member carried by said base and insulated therefrom, means for connecting said contact member with the terminals of the batteries in the other two of said compartments, an electric light bulb mounted in said base and having a central terminal in contact with said contact member.

5. In a device of the class described, a casing divided into four compartments each of said compartments being adapted to receive a battery, a base for said casing, means for connecting said base with the batteries in two of said compartments, a contact member carried by said base and insulated therefrom, means for connecting said contact member with the terminals of the batteries in the other two of said compartments, an electric light bulb mounted in said base and having a central terminal in contact with said contact member, and means for electrically connecting the upper terminals of said batteries.

6. In a device of the class described, a casing divided into four compartments each of said compartments being adapted to receive a battery, a base for said casing, means for connecting said base with a terminal of each of the batteries in two of said compartments, a contact member carried by said base and insulated therefrom, means for connecting said contact member with a terminal of each of the batteries in the other two of said compartments, an electric light bulb mounted in said base and having a central terminal in contact with said contact member, and means for electrically connecting the upper terminals of said batteries, said means serving to establish a circuit thru said light bulb regardless of whether two or four batteries are installed in said compartments.

7. In an electric hand lantern, a casing, an insulating disc mounted in the upper part of said casing, a pair of contact members carried by said insulating disc, each of said contact members having a downwardly extending contact portion adapted to contact with a terminal of a battery, each of said contact members having another contact portion extending upwardly thru said disc and switch means for electrically connecting the contact portion above said disc.

8. In an electric hand lantern, a battery casing, an insulating disc mounted in the upper part of said casing, a pair of contact members carried by said insulating disc, each of said contact members having a battery contacting portion extending below said disc and a switch contacting portion extending thru and above said switch, a flexible switch portion carried by said disc, a slidible operating member carried by the cover of said casing, said operating member being adapted to move said switch member into contact with both of said contact members to form an electrical connection therebetween.

9. In an electric hand lantern, a casing having four battery compartments, an insulating disc in the upper part of said casing, a pair of contact members carried by said insulating disc, each of said contact members having a contact portion extending into two of said battery compartments and adapted to contact a terminal of the battery therein, said two contact members being normally insulated from each other and a switch mounted on the cover of said casing for establishing contact between said two contact members.

10. In an electric hand lantern, a sheet metal battery casing, an insulating disc mounted in the upper end of said casing, a pair of contact members carried by said insulating disc, each

of said contact members having a portion adapted to contact the terminals of one or more batteries and another portion adapted to contact a switch member, a flexible switch member carried by said insulating disc and adapted to form an electrical connection between said contact members, a slidible member mounted on the battery casing for operating said switch member, and means for insulating said switch member from said slidible member.

11. In a device of the class described, a casing divided into four compartments, each of said compartments being adapted to receive a battery, means for connecting said casing with the batteries in two of said compartments, a contact member insulated from said casing, means for connecting said contact member with one of the terminals of each of the batteries in the other two of said compartments, an electric light bulb having a central terminal in contact with said contact member, means for connecting the other terminals of said batteries, and means for connecting and disconnecting the circuit.

12. In a device of the class described, a casing divided into four compartments, each of said compartments being adapted to receive a battery, a base for said casing, means for connecting said base with the batteries in two of said compartments, a contact member insulated from said base, means for connecting said contact member with one of the terminals of each of the batteries in the other two of said compartments, an electric light bulb mounted in said base and having a central terminal in contact with said contact member, means for connecting the other terminals of said batteries, and means for connecting and disconnecting the circuit.

13. In a device of the class described, a casing divided into four compartments each of said compartments being adapted to receive a battery, means for connecting said casing with a terminal of each of the batteries in two of said compartments, a contact member carried by said casing and insulated therefrom, means for connecting said contact member with a terminal of each of the batteries in the other two of said compartments, an electric light bulb mounted in said casing and having a central terminal in contact with said contact member, and means for electrically connecting the upper terminals of said batteries, said means serving to establish a circuit thru said light bulb regardless of whether two or four batteries are installed in said compartments.

ALFRED C. KORTE. 55
